(57) CLAIM

The ornamental design for a visual aid for aligning vehicle trailer hitch, as shown and described.

DESCRIPTION

FIG. 1 is a perspective view of the visual aid for aligning vehicle trailer hitch embodying the design of the present invention;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof;

FIG. 6 is a bottom plan view thereof; and,

FIG. 7 is a reduced perspective view showing the visual aid for aligning vehicle trailer hitch in use; the broken lines depict environmental structure and form no part of the claimed design.
